UNITED STATES PATENT OFFICE.

ERIK L. KRAG, OF CHICAGO, ILLINOIS.

LOOSE-LEAF BINDER.

1,391,780.

Specification of Letters Patent. Patented Sept. 27, 1921.

Application filed November 14, 1918. Serial No. 262,512.

To all whom it may concern:

Be it known that I, ERIK L. KRAG, of Chicago, in the county of Cook and State of Illinois, have invented certain new and useful Improvements in Loose-Leaf Binders, of which the following is a description, reference being had to the accompanying drawings, forming a part of this specification, in which corresponding numerals of reference 10 in the different figures indicate like parts.

The object of my invention is to provide a simple, cheap, durable and effective loose-leaf binder of the type in which counterpart leaf-holding prongs are mounted upon opposing binding members hinged to each other for holding interposed leaves. In forming structures of this kind it is necessary to construct the cover proper with its supporting or stiffening members and the 15 intermediate binding and locking portions separately and then attach them together so as to form an operative whole. My aim is to so construct said cover supporting members and cover therefor as to present a finished 20 and attractive appearance when completed without having objectionable rivet heads or parts of other fastening devices projecting therefrom, at the same time providing and arranging such fastening devices as to enable the cover members proper to be quickly 25 and firmly attached to the binding members, as the result of a single operation; all of which is hereinafter more particularly described and definitely pointed out in the 30 claims:

In the drawings:

Figure 1, is an end view in detail of the cover supporting members as they would appear when detached but in the relative 40 positions which they would assume with respect to each other when the binder is closed.

Fig. 2, is an end view partly in section of a binder as it would appear with the parts in locked relation, the covers being open and 45 broken away,

Fig. 3, is an end view as it would appear when unlocked and partly open, and

Fig. 4, is a transverse section through one of the metal cover-supports, showing a modified construction.

Referring to the drawings, 1 and 2 designate the cover supporting or stiffening members which are preferably formed from sheet-metal corresponding in length to that 55 of the cover. Said members are provided

respectively with inturned flanges 3 and 4, which are extended toward each other with an intervening space between them. Filling or thickening members 5, 6, corresponding in length to said stiffening members and 60 preferably formed from paste-board or wood, are secured to the inner faces of said stiffening members. In the preferred construction for large binders, flat-headed rivets 7, 8, are used, which have their heads 65 countersunk in the members 1 and 2 with the bodies extending therethrough and through the members 5 and 6 and projecting inwardly therefrom for the purpose hereinafter stated. When the parts 1, 5 and 7 and 2, 70 6 and 8, respectively, are thus assembled, the cover-supports 1 and 5 and 2 and 6 have a covering 9, of leather, cloth, canvas or other suitable material applied, by means of an adhesive medium, upon opposite sides 75 thereof, as shown in Fig. 2, so as to inclose said members while connecting them by means of an intermediate flexible connection 10. Said covering material is also extended over the usual stiffening lids 11, 12, so as to 80 provide ordinary intervening hinged portions 13 and 14. When the parts are thus assembled the heads of the rivets 7 and 8 are hidden beneath a smooth outer surface 85 and the parts are in condition to be connected to the binding members proper, indicated generally by 15 and 16. Said members are formed from sheet-metal having primary portions 17, 18, hinged together at 90 19. Said members are bent laterally in opposite directions at 20 and 21 at right angles to their respective planes and again at 22 and 23, thus forming secondary portions 24 and 25 and flange portions 26 and 27, which are provided with suitable perforations to 95 receive fastening devices such for example, as the projecting rivets 7 and 8, respectively.

Sheet metal plates 28, 29, are rigidly attached respectively to the flanges 26 and 27 by means of rivets 30 and 31, and are provided with the usual counterpart prongs 32, 33, which are rigidly attached thereto to hold loose leaves in place when the binding members are locked together. A slidable locking-member 34 consisting of a flat elongated 100 bar is loosely secured in suitable guides 35 upon the outer face of the member 25. Said bar is provided with one or more detents 36, adapted to enter slots in the part 17, so as to engage the latter and lock the parts 17 and 110

18 together in the manner indicated in Fig. 2. Said locking bar may be held in a normal position by means of a coiled-spring in a well known way and is provided with a handle portion 37, to enable it to be actuated.

In assembling the parts, the rivets 7 and 8 of which there may be two or more for each of these parts 1 and 2, are projected through 10 the perforations in the flanges 26 and 27, and washers 38, 39, placed thereon, when said rivets may be upset, thereby permanently securing the binding and cover members together. It is obvious that this may be done 15 by a single operation, thus reducing the cost of assembling to a minimum.

In Fig. 4, I have shown a modified means for connecting the cover-supports with the binding members. In lieu of the rivets 7 20 and 8, elongated lugs 40, may be cut from the metal members 1 and 2 by means of a die and bent inwardly at right angles to the body of the metal so as to extend through openings in registration therewith in the 25 flanges 26 and 27. Thus, when the parts are assembled, said lugs may be bent or flattened upon the inner faces of said flanges, thereby holding the latter rigidly in place.

Having thus described my invention, I 30 claim:

1. In a loose-leaf binder, a pair of pivotally connected angular inner binding members having opposite side flange portions adapted to extend in substantially parallel 35 relation to each other when in normal closed position, and each provided with perforations for receiving fastening means, a pair of rigid angular cover-supporting members spaced apart at their rear margins, each of 40 said rigid angular cover-supporting members comprising in its construction a rigid

main body portion located outside of and in parallel relation to a perforated flange portion of a corresponding inner angular binding member, fastening means on said main body portions of said rigid angular cover-supporting members and extending into said perforations in the inner pivotally connected angular binding members, and flexible covering material upon the said rigid angular cover-supporting members and covering said fastening means and said rigid angular cover-supporting members, and forming a flexible connection between the spaced apart rear margins of the latter. 55

2. In a loose-leaf binder, the combination of a pair of rigid cover-supporting members having parallel side portions each adapted to be connected with a cover leaf, each of said rigid cover-supporting members having a rear portion extending toward but spaced apart with respect to the opposite rigid cover-supporting member, a pair of pivotally connected inner flanged binding members connected with said side portions of said rigid cover-supporting members, flexible covering material upon both sides of and covering said rigid cover-supporting members and forming inner and outer flexible connecting hinge portions between the rear margins of said rigid cover-supporting members, and means for locking said pivotally connected inner flanged binding members together. 70

In testimony whereof, I have signed this 75 specification in the presence of two subscribing witnesses, this twelfth day of November, 1918.

ERIK L. KRAM.
